UNITED STATES PATENT OFFICE.

JOHN A. FLEMINGS, OF SHARON, MASSACHUSETTS, AND ERNEST B. PRIEBE, OF WILKINSBURG, PENNSYLVANIA, ASSIGNORS TO B. F. STURTEVANT COMPANY, OF HYDE PARK, MASSACHUSETTS, A CORPORATION OF MASSACHUSETTS.

FURNACE.

Application filed December 14, 1918. Serial No. 266,767.

To all whom it may concern:

Be it known that we, JOHN A. FLEMINGS and ERNEST B. PRIEBE, citizens of the United States, residing at Sharon, in the county of Norfolk and Commonwealth of Massachusetts, and at Wilkinsburg, in the county of Allegheny and State of Pennsylvania, respectively, have invented certain new and useful Improvements in Furnaces; and we do hereby declare the following to be a full, clear, and exact description of the invention, such as will enable others skilled in the art to which it appertains to make and use the same.

15 The invention relates to furnaces of the underfeed type, in which the fuel is fed into the furnace below the fuel bed and below the openings for the air supply, whereby the fuel is first coked and the volatile matter 20 liberated and then consumed upon passing through the burning layer of fuel.

In furnaces embodying the preferred form of the invention the fuel is fed to the combustion chamber through one or more 25 underfeed retorts extending from the front toward the rear longitudinally of the fire box. Overfeed grates are arranged along the side walls of the retorts, which are stationary immediately adjacent the retorts 30 but movable at their outer portions to provide means for a progressive advance of the fuel bed toward the bridge wall over the intermediate overfeed grates, and to and over a stationary auxiliary grate at the rear of 35 the retorts. An adjustable ash plate is provided at the rear of the auxiliary grate, and receives the ash or refuse from the grate surfaces. The discharge of the ash from the ash plate is facilitated by a series of 40 clearing bars, adapted to reciprocate vertically adjacent the bridge wall, the movements thereof acting to clear the face of the bridge wall and to disintegrate the ash and permit a definite amount to be released 45 from the ash plate.

For a detailed illustration of one form of apparatus embodying the invention, reference may be had to the following description and to the accompanying drawings 50 forming a part thereof, in which Figure 1 is a plan view, partly in section, showing the relative arrangement of the retorts, grates and feeding mechanism; Fig. 2 is a vertical sectional view taken substantially

on the line A—A, Fig. 1; Fig. 3 is a similar 55 sectional view taken substantially on the line B—B, Fig. 1; and Fig. 4 is a vertical transverse sectional view taken substantially on the line C—C, Fig. 2.

In the drawings the numeral 1 indicates 60 the front wall of a furnace of any well-known or preferred type, and 2 the bridge wall thereof. Between these walls, and in the fire box or combustion chamber, are located the various grates and retorts comprising the automatic stoker for the continuous feeding of fuel to the boiler. In the present form of the invention there are 65 a plurality of retorts 3, having reciprocating bottoms 4. The fresh fuel is forced into 70 these retorts through the flaring openings 5 by means of the well-known plungers 6, as clearly shown in Fig. 2. The bottoms 4 of the retorts 3 are reciprocated by being connected with the operating means for the 75 plungers through the intermediary of the bar 7, the lever 8 and the rock shaft 9, which is oscillated by an arm 10 connected with an operating bar 11 adapted to engage an abutment or angle iron 12 carried by the 80 plunger 6.

Referring to Figs. 1 and 2, it will be seen that at the sides of the retorts 3 are stationary blocks 13 having openings 14 for supplying air to coke the fresh fuel prior to its 85 passage into the burning layer thereof. These blocks also constitute stationary grate sections extending longitudinally of the sides of the retorts. Beyond the stationary grate sections adjacent the walls of 90 the retorts, and between the same and the side walls of the combustion chamber, are reciprocating grate sections in the form of 95 grate bars which comprise supports 15 upon which are secured grate blocks provided with air passages 16, as indicated in section in Figs. 3 and 4. These supports are caused to reciprocate in a manner similar to that of the bottoms of the retorts, by being connected with the rock shaft through the lever 100 17 and the bar 18.

Just below the inner ends of the overfeed 105 grate bars are auxiliary stationary grate bars 19 also having air openings as indicated in section in Figs. 2 and 3. Between the auxiliary grate 19 and the bridge wall 2 is an adjustable ash plate 20 which is moved forward or back to regulate the opening for the

discharge of ash, by means of the racks 21 engaging pinions 22 on the transverse shaft 23. The shaft 23 may be rotated to move the ash plate by any suitable means (not shown) either at the side or in front of the boiler.

A continuous discharge of the ash, clinkers and other refuse is ensured by means of a series of clearing bars 24 provided with holes 10 low heads 25 having inclined front surfaces, and air openings 25' for the passage of air from the ash pit through the heads and between the heads and bridge walls. All or some only of these bars may be caused to 15 reciprocate along the front of the bridge wall 2 by means of racks 26 and pinions 27, which latter are carried on the transverse shaft 28. This shaft is oscillated by means of suitable connections (not shown) with 20 the feeding mechanism for the fuel, above mentioned.

The space 29 is separated from the space 30 by the partition 31 and the supports 32, or other suitable means.

25 Air under pressure, for a forced draft, is supplied to the chamber 29 below the retorts and intermediate overfeed grates, while the auxiliary stationary grate 19 is preferably supplied by air under natural draft from 30 the ash pit 30.

Adjustment of the amount of movement of the bottoms of the retorts and of the reciprocating grates is obtained by the filling pieces 33 on the ends of the bars 7 and 18, 35 and whose removal or introduction allows more or less lost motion between the pin and slot which connects the bars to the levers 8 and 17 respectively whereby the movements of said bars are decreased or increased.

40 By the above features of construction a minimum weight of movable parts is attained, while at the same time the fuel is fed positively and continuously at points where positive motion is most desirable.

45 The vertically reciprocating clearing bars have somewhat the action of a slicing bar, and keep the surface of the bridge wall free from clinker and heavy scale, the inclined surfaces acting to force the ash outward, 50 thus ensuring a positive removal of ash and preventing the banking of dead ash against the bridge wall. The upward strokes of the clearing bars tend to lift the refuse off the ash plate and separate it from the glowing 55 and softer unburned portions, so that there is practically no discharge until the fuel is wholly consumed.

The use of intermediate reciprocating

grate bars between the stationary grate bars at the sides of the retorts permits a substantial increase in the effective surfaces of the overfeed grates to which the coked fuel is delivered from the retorts, and at the same time ensures a substantially continuous and uniform movement of the entire fuel bed, 65 thus increasing the efficiency of the stoker and rendering it particularly applicable to large installations. The intermediate stationary sections of the grates also ensure a more positive retention of the fuel during 70 the outward strokes of the movable sections and of the bottoms of the retorts.

What is claimed is:—

1. A furnace, having, in combination with a fire box, an underfeed retort having air 75 conducting and discharging means at the sides and above the bottom thereof and forming fixed grates at the sides of said retort, said retort having a movable bottom, movable grate sections at the sides of the fixed 80 grates, and means for simultaneously reciprocating said grate sections and the bottom of said retort.

2. A furnace, having, in combination with a fire box, underfeed retorts having air conducting and discharging means at the sides and above the bottoms thereof and forming grates at the sides of said retorts, said retorts having movable bottoms, a plurality of 85 intermediate movable grate sections between 90 the retorts, and means for reciprocating adjacent intermediate movable sections in opposite directions and simultaneously with the movement of the bottoms of the respective retorts.

3. A furnace, having, in combination with a fire box, underfeed retorts, grates having movable portions for advancing the fuel and provided with air conducting and discharging means, an auxiliary stationary grate at the rear of said retorts and said grates, and an ash plate adapted to receive the fuel from 95 said auxiliary grate.

4. A furnace, having, in combination with a fire box, underfeed retorts, grates having relatively movable and fixed portions and provided with air conducting and discharge means, an auxiliary fixed grate at the rear of said retorts and said former grates, and means for segregating the spaces below said former and said auxiliary grates to permit 100 the supply of air under pressure to said former grates and air under natural draft to 105 said auxiliary grate.

JOHN A. FLEMINGS.
ERNEST B. PRIEBE.
